UNITED STATES PATENT OFFICE

SAMUEL MARCUS, OF RIVERDALE, NEW YORK, ASSIGNOR TO MARKON MANUFACTURING CO., INC., OF NEW YORK, N. Y., A CORPORATION OF NEW YORK

ROLLING EYES FOR DOLLS

Application filed June 6, 1929. Serial No. 368,897.

This invention relates to an improvement in rolling eyes for dolls.

An object of the invention is to provide an eye set in which the eyes are capable of ample pivotal movement in various directions about their spherical centres under the gravity control of a single weight element.

A further object is to provide an eye set which may be quickly and easily assembled 10 or disassembled and in which the eyes are capable of easy and convenient universal adjustment with respect to each other about their spherical centres and in which the eyes are readily adjustable toward and away 15 from each other.

A further object is to provide an eye set as above and including an attaching or carrier member by which to connect it with the doll head, the only connection between the 20 carrier and the remainder of the eye set being a pivotal connection in the region between the two eyes of the set in such manner that the carrier may be connected with the head either in the space between the eyes, 25 or otherwise as preferred.

A further object is to provide an eye set made up of parts which are of simple and inexpensive form and construction.

A more specific object is to provide an eye 30 set in which the eyes are carried upon a pair of vertical pivot rods and in which said rods are connected together by means which permits of their easy adjustment toward and away from each other while maintaining 35 their vertical alignment and which provides a horizontal pivot forming portion intermediate the eyes for pivotal connection with the carrier.

A further detailed object is to so design 40 the set that the part thereof which connects together the vertical eye-carrying rods serve for attachment of the rod and a stop element therefor.

A further detailed object is to provide improved limiting means for limiting the gravity oscillatory movements of the vertical eye-carrying rods.

Other objects and aims of the invention, 45 more or less specific than those referred to above, will be in part obvious and in part

pointed out in the course of the following description of the elements, combinations, arrangements of parts and applications of principles constituting the invention; and the scope of protection contemplated will be 55 indicated in the appended claims.

In the accompanying drawings which are to be taken as a part of this specification, and in which I have shown merely a preferred form of embodiment of the invention: 60

Fig. 1 is a rear elevational view of an eye set constructed in accordance with this invention, a part of the set being broken away for better disclosing details of construction, 65 and the whole being illustrated in position within a doll head shown in vertical section.

Fig. 2 is a horizontal sectional view upon the plane of line II—II of Fig. 1.

Fig. 3 is a vertical sectional view upon the plane of line III—III of Fig. 1.

Fig. 4 is a vertical sectional view upon the plane of line IV—IV of Fig. 1, and

Fig. 5 is an enlarged fragmentary perspective view of parts of the eye set appearing in the above figures.

Referring now to the drawings for describing in detail the construction which is illustrated therein, the reference character L indicates a doll head having the usual eye 50 sockets 1 and 2 therein at opposite sides of the central or nose portion 3.

The eye set at present illustrated consists of a horizontal supporting carrier G of the general type as shown in the pending application of Alexander Konoff, Serial No. 141,943 in that it comprises a main body member 4 upon which is slidably mounted a pair of attaching members 5—5 adapted to be thrust from opposite ends of the body into firm attachment with the side walls of the doll head to thereby rigidly connect the carrier in position spanning the interior of the head, the outer end of the attaching member having tangs as 6—6 thereon for being embedded within the opposite side wall portions 7—7 of the head. Projecting forwardly from the body member 4 is a pair of arms as 8—8 the forward ends of which are shaped to provide bearings as 9—9 spaced 100

apart for pivotally receiving the pivot portions as 10—10 of the device which connects the two eyes together.

The eyes, illustrated generally by the reference characters H—H, may be formed in any appropriate manner, but according to the present illustration each is made up of inner and outer semispherical shell members as 11 and 12 respectively. These may be of 5 any appropriate material, but usually sheet metal is employed for the inner shell and celluloid for the outer shell, the two shells being fitted snugly one within the other but there being sufficient freedom of movement 10 between the shells so that the outer shell may be rotatably adjusted with respect to the inner shell about the common spherical centre if found necessary, such adjustment being about a horizontal axis transverse to a 15 straight line between the centres of the two eyes.

At the rear of each eye there is provided a flat metallic plate 13 which has substantially integral connection with the inner shell 11 20 in restricted areas horizontally at opposite sides, as at 14 and 15, of the spherical centre of the eye, that is in the plane of a straight line between the centres of the two eyes, and these restricted connections are pliable so 25 that the shell portions of the eyes may be readily adjusted with respect to the plates by bending of said connections, the attachment thus afforded being about a horizontal axis co-incident with a straight line between 30 the centres of the eyes.

Each of the plates 13 is formed to provide a spring socket therein adapted to receive one of the eye-carrying rods 16—16 projecting substantially vertically upward into the 35 socket so as to constitute connections between the eyes and their respective rods affording manual adjustment of the eyes with respect to the rods upon vertical axes intersecting the spherical centres of the eyes. These 40 sockets may take any appropriate form but are preferably constructed from alternately pressed portions of the plates 13 after the manner fully illustrated and described in the pending application of Samuel Marcus, Serial No. 334,896.

The rods 16 are each formed with a lateral projection 17 for engaging one of the socket forming straps or sections as 18 to limit the distance to which the rod may be thrust into 50 the socket.

The shell portions of each eye are cut away as at 19 at their lower sides to accommodate the rods 16 and to provide sufficient space so as not to interfere with the desired adjustments of the shells above described.

The connecting device between the two rods 16 is sectional, that is it consists of two identical pieces or sections as 20—20. Each of these is shaped at its outer end to provide 60 a pair of vertically aligned bearings as 21

and 22 spaced apart through which the adjacent rod 16 extends so that the rods are vertically rotatably mounted in said bearings, the points of engagement between said sections and the rods being in the regions below the bottom edge of the eyes, the eyes being attached to those portions of the rods which project upwardly above the bearings.

The sections 20 project from the rod 16 70 toward each other and are curved upwardly about the respective eyes. The adjacent end portions of the respective sections are shaped to provide annular sleeves, heretofore designated by the reference characters 10—10, adapted to receive a bonding rod 23 which 75 extends through both sleeves to provide a bond between them.

The bonding rod 23 is of rectangular cross section and the interior of the sleeves is of a contour to utilize the angular relationship of 80 the surfaces of the rod so as to prevent any rotary movement of the sleeves with respect to the rod, while yet permitting endwise sliding of one or both of the sleeves along the 85 rod whenever it is desired to adjust the sections 20—20, and the rods 16—16, toward or away from each other. As a simple means by which to afford the required connection between the sleeves and the rod, and to at 90 the same time provide a spring friction grip 95 of the sleeves upon the rod, the drawing herewith suggests that the sleeves, and in fact the entire sections 20—20, may be formed of sheet metal, the sleeves consisting merely of 100 cylindrically bent extensions of said sections, so that the sleeves are each split as at 105 24 and thus made relatively resilient. The bonding rod 23 may be made of relatively harder metal than the material of the split sleeves so that the operation of forcefully 110 bending the sleeve forming portions of the sections about said rod during manufacture will cause the longitudinal corners as 25—25 of the rod to bite relatively into the inner 115 surface of the sleeves so as to produce grooves as 26—26 within said sleeves co-operative with the corners or ribs 25 to permit longitudinal sliding of the sleeves but preventing 120 all rotary movement.

The sleeves 10—10 of course stand in a horizontal position. They are maintained in alignment by the presence of the bonding rod 23 within them at all times, and the upward bending of the sections 20 disposes them so that their pivotal axes co-incides with the position of a straight line between the spherical centres of the eyes.

Any appropriate means may be employed for retaining the eye-carrying rods 16—16 125 against endwise movement in their bearings 21 and 22. As a simple expedient to this end however the drawing herewith suggests that each of these rods may be provided with a lateral projection as 27 thereon extending 130 into the space between the portions as 28 and

29 which provide the bearings 21 and 22. These projections are arranged to engage the opposing surfaces of the portions 28 and 29.

The portions 28 and 29 may be provided 5 with slots as 30 and 31 respectively, communicating with the bearings 21 and 22, for permitting passage of the projections 17 and 27 of the rods 16 during assembly, it being noted that the slots are placed in such radial 10 positions as not to register with the projection 17 or 27 during any normal operation of the eye set mechanism.

The weight employed for the gravity control of the eyes is indicated by the reference 15 character 32. It is attached to the lower end of a rod or wire 33, the upper end portion as 34 of which is pivotally connected to swing about a relatively vertical axis in a bracket piece 35 which is in turn connected with the 20 sleeves 10—10 of the sections 20.

The bracket piece 35 is formed from a small strip of sheet metal having its upper end portion bent to constitute a sleeve or cylinder 36 which is adapted to fit loosely 25 about the sleeves 10—10 collectively. Its lower portion is bent to provide a pair of spaced bearings as 37 and 38 within which the portion 34 of the weight carrying wire is mounted, the wire having a head as 39 beyond the upper bearing, and being bent laterally as at 40 beneath the lower bearing, for preventing endwise displacement of the wire from said bearings. The lateral bending of the wire beneath the lower bearing also disposes the weight 32 in a position rearwardly 35 of the pivotal axis of the portion 34 so that the weight will swing by gravity from side to side within the bearings 37 and 38 whenever the doll is tilted sidewise.

40 The bracket piece 35 is provided with a spring tongue 41 projecting forwardly therefrom adapted to engage against an inner surface portion of the doll head for limiting swinging movement of the bracket piece in a 45 direction toward the head.

Each of the eye-carrying rods 16 is provided with rearwardly extending portion as 42 at its lower end and these extending portions are connected together by a connecting link 43 which is pivotally connected with the rear end of each extension so that the eyes are always obliged to move in unison within the bearings 21 and 22. The link 43 has a central opening 44 through which the 55 relatively horizontal extending portion 40 of the rod loosely passes so that sidewise swinging of said rod by gravity force of the weight will impart corresponding movement in either direction to the eyes.

50 The opening 44 is of such length that its opposite end walls will engage against the rod 40 to limit sidewise swinging of the weight in both directions, and the link is preferably formed of resiliently flexible material 55 so that the impact of the rod against the end

walls of the opening or slot 44 will be resiliently cushioned and thus made practically noiseless.

The manner of connecting the link 43 with the extension 42 may take any appropriate 70 form, but in the instance illustrated it consists merely in providing the extensions 42 each with two pairs of lugs, as 45—45 and 46—46, spaced apart to receive the link between them, the link being formed with a 75 suitably large opening as 47 to loosely receive the portion as 48 of the extension 42 which lies between the pairs of lugs, and the link having suitable slots as 49—49 therein 80 communicating with the opening 47 to enable assembly of the parts, the slots 49 being in such radial positions as not to permit passage of the lugs after the parts have been assembled.

In assembling the eye set as here described 85 the rods 16 are first attached to their respective sections 20 of the connecting device, then with opposite ends of the link 43. This done their sleeves 10—10 are telescoped onto the bonding rod 23 and into the sleeves 36 90 of the bracket piece 35. This assembly is extremely simple and requires no tools, yet when completed is such that the parts have appropriate freedom of rotary movement 95 with respect to each other without possibility of accidental disassembly.

The eyes may be telescoped downwardly onto the upper ends of the rods 16 after the other parts are entirely assembled.

In forming the sleeves 10 of sections 20 for 100 engaging the bonding rod 23, these sleeves may be formed directly on the rod 23 if desired, but they preferably are formed upon a rod which is identical with rod 23 but of slightly less cross sectional contour than the rod 23 so that when the sleeves are assembled onto the rod 23 the insertion of rod 23 will spring the sleeves open to a slight degree sufficient to generate the desired spring grip of the sleeves upon the rod. 105

110 It will be understood that oscillatory movement of the eyes about the horizontal axis provided by the bearings 9—9 in the carrier G will be caused by gravity movement of weight 32 incident to tilting of the doll forwardly or backwardly in the usual manner.

115 While the sleeve portions 10—10 of the connecting device are described as having tight frictional engagement with the bonding rod and the cylinder 36 of the bracket 120 piece 35 is described as being loose upon the sleeve portions, this may be reversed if desired, and in fact in some cases it may be sufficient to omit the bonding rod and depend upon a tight frictional grip of the cylinder 125 36 about the exterior surface of the sleeves to hold said sleeves assembled, or if desired the sleeves may be only loosely connected with both the bonding rod and the cylinder so that they may move freely longitudinally 130

toward and away from each other, engagement of the eyes within the sockets of the head being depended upon in this latter instance to hold the sleeves against disassembly.

5 As many changes could be made in this construction without departing from the scope of the invention, as defined in the following claims, it is intended that all matter contained in the above description, or shown 10 in the accompanying drawings, shall be interpreted as illustrative only and not in a limiting sense.

Having thus described my invention, what I claim as new and desire to secure by Letters Patent is:—

1. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier having parts for connection with a doll head and having another part co-operative with said connecting device to provide pivotal engagement between the connecting device and the carrier upon a substantially horizontal axis co-incident with a straight line between the centres of the eyes so that the eyes are adapted to oscillate upon a horizontal axis, and gravity acting means selectively operable to swing the eyes upon said horizontal axis and said vertical axes.

2. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier having parts for connection with a doll head and having another part co-operative with said connecting device to provide pivotal engagement between the connecting device and the carrier upon a substantially horizontal axis co-incident with a straight line between the centres of the eyes so that the eyes are adapted to oscillate upon a horizontal axis, the downwardly projecting portions of the eye carrying rods each having a rearwardly projecting lateral extension thereon, a link by 55 which the rear end portions of said extensions are pivotally connected together, and a weight connected with said link.

3. An eye set comprising a pair of eyes, a pair of vertically disposed rods upon which the eyes are carried respectively, said rods

having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier having parts for connection with a doll head and having another part co-operative with said connecting device to provide pivotal engagement between the connecting device and the carrier upon a substantially horizontal axis co-incident with a straight line between the centres of the eyes so that the eyes are adapted to oscillate upon a horizontal axis, the downwardly projecting portions of the eye carrying rods each having a rearwardly projecting lateral extension thereon, a link by which the rear end portions of said extensions are pivotally connected together, a weight, and a weight rod extending from said weight into pivotal engagement with said connecting device, said rod having pivotal engagement also with said link at a point intermediate the length of the rod.

4. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier having parts for connection with a doll head and having another part co-operative with said connecting device to provide pivotal engagement between the connecting device and the carrier upon a substantially horizontal axis co-incident with a straight line between the centres of the eyes so that the eyes are adapted to oscillate upon a horizontal axis, the downwardly projecting portions of the eye carrying rods each having a rearwardly projecting lateral extension thereon, a link by which the rear end portions of said extensions are pivotally connected together, a weight, and a weight rod extending from the weight loosely through an aperture provided in the mentioned link and into pivotal attachment with the mentioned connecting device so that pivotal swinging of the weight about its pivotal attachment with the connecting device will swing the eyes about their vertical axes, the aperture in the link having opposite side walls to engage the weight rod for limiting swinging movement of the weight in both directions.

5. An eye set comprising a pair of eyes, a pair of vertically disposed rods upon which the eyes are carried respectively, said rods having portions projecting downwardly be-

- neath the lower edges of the eyes, a connecting device extending between said rods providing bearings within which the downward projecting portions of the rods are oscillatably mounted so that the rods and eyes are adapted to oscillate upon substantially vertical axes, a supporting carrier having parts for connection with a doll head and having another part co-operative with said connecting device to provide pivotal engagement between the connecting device and the carrier upon a substantially horizontal axis co-incident with a straight line between the centres of the eyes so that the eyes are adapted to oscillate upon a horizontal axis, the downwardly projecting portions of the eye carrying rods each having a rearwardly projecting lateral extension thereon, a link by which the rear end portions of said extensions are pivotally connected together, a weight, a weight rod extending from the weight loosely through an aperture provided in the mentioned link and into pivotal attachment with the mentioned connecting device so that pivotal swinging of the weight about its pivotal attachment with the connecting device will swing the eyes about their vertical axes the aperture in the link having opposite side walls to engage the weight rod for limiting swinging movement of the weight in both directions, and said link being resiliently flexible to thereby cushion the action of said limiting means.
6. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier having parts for connection with a doll head and having another part co-operative with said connecting device to provide pivotal engagement between the connecting device and the carrier upon a substantially horizontal axis co-incident with a straight line between the centres of the eyes so that the eyes are adapted to oscillate upon a horizontal axis, gravity acting means selectively operable to swing the eyes upon said horizontal axis and said vertical axes, said connecting device consisting of two separately formed sections having pivotal connection with the eye carrying rods respectively, and means by which said two sections are connected together providing for manual adjustment of said sections in directions toward and away from each other.
7. An eye set comprising a pair of eyes, a connecting device by which the eyes are connected together, said connecting device consisting of two separately formed sections
- upon which the eyes are mounted respectively, each of said sections having a sleeve portion thereon, a separate rod upon which said sleeve portions are slidably telescoped to hold said sections connected for adjustment in directions toward and away from each other and to hold said sleeve portions in axial alignment, said rod being of rectangular cross section providing sharp longitudinally extending corners thereon and being of a material relatively harder than the material of the sleeve portions, and said sleeve portions having sliding engagement with said sharp corners to retain said sleeve portions against relative rotary movement upon the rod while yet permitting sliding of the sleeve portions along the rod, said aligned sleeve portions being disposed co-axially with a straight line extending between the centres of the eyes, a supporting carrier having one part for connection with a doll head and having another part providing a pivotal bearing within which said sleeve portions engage to thereby provide a pivotal mounting for the eyes upon a horizontal axis, and a gravity control for the eyes.
8. An eye set comprising a pair of eyes, a pair of vertically disposed rods upon which said eyes are mounted respectively, a connecting device extending between and connecting said rods together, said connecting device providing a pair of spaced pivot bearings for each of said rods, each of said rods having a lateral projection thereon arranged in the space between the pair of bearings within which it is pivotally mounted whereby to prevent endwise movement of the rods with respect to said bearings, gravity means to swing the rods in said bearings, means normally operative to limit the swinging of said rods, at least one bearing of each of said pairs having a radial slot therein to permit passage of the lateral projection of the respective rod upon rotary movement of said rod to an abnormal position.
9. An eye set comprising a pair of eyes, a pair of vertically disposed rods upon which said eyes are mounted respectively, a connecting device extending between and connecting said rods together, said connecting device providing a pair of spaced pivot bearings for each of said rods, each of said rods having a lateral projection thereon arranged in the space between the pair of bearings within which it is pivotally mounted whereby to prevent endwise movement of the rods with respect to said bearings, the rods projecting upwardly from said bearings and into sockets of the eyes so as to support the eyes above said bearings, gravity means to swing the rods in said bearings, means normally operative to limit the swinging of said rods, each of said rods having a second lateral projection thereon spaced above the bearings adapted to be engaged by the eyes for limit-

ing movement of the rods into the sockets of the eyes, and all of said bearings having radial slots therein to permit passage of the lateral projections of the rods upon rotary movement of said rods to abnormal positions.

5 10. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

15 20. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

25 30. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

35 40. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

45 50. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

55 60. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

65 70. An eye set comprising a pair of eyes, a pair of vertically disposed rods upon which the eyes are carried respectively, said rods having portions projecting downwardly beneath the lower edges of the eyes, a connecting device extending between said rods providing bearings within which the downward projecting portions of the rods are oscillatably mounted so that the rods and eyes are adapted to oscillate upon substantially vertical axes, a supporting carrier, and weighted lateral extensions provided upon said vertical rods to oscillate said rods and eyes by gravity.

pivottally attach the weight rod to the eye connecting device to swing upon a vertical axis, said weight rod having engagement with the link to swing the eyes by gravity movement of the weight, and said attaching member having a part constituting a bumper to cushion movement of the eye connecting device upon said horizontal axis.

In testimony whereof I affix my signature.
